WARP BEAM FOR LOOMS

Frank D. Lindquist, Worcester, Mass., assignor to
Crompton & Knowles Loom Works, Worcester,
Mass., a corporation of Massachusetts

Application September 30, 1948, Serial No. 51,930

6 Claims. (Cl. 242—124)

1

This invention relates to improvements in warp beams for looms and it is the general object of the invention to provide simple and efficient means for holding the warp heads securely to the beam barrel in adjusted position along the latter.

The warp of a loom is ordinarily wound on a beam which is rotatably mounted at the back of the loom and is drawn forwardly from the beam through harness frames. In recent years there has been a tendency to increase the diameter of warp beams so they can hold a large amount of warp thread suitable for weaving operations extending over several weeks. The end pressure of the warp threads in such beams is very high and exerts forces tending to distort the flange or heads of the beam and cause them to slide along the beam barrel.

It is an important object of the present invention to provide a warp head with a wedge which can be drawn transversely of the warp beam to exert a considerable force between the warp head and the barrel to prevent relative slippage of these parts.

It is a further object of the invention to provide a warp beam with a barrel member having screw threads cut thereon and a warp head threaded on to said screw threads and held in position by a wedge which fits the screw threads of the barrel and is so mounted that it can be moved transversely of the barrel in the general direction of the length of the screw threads to establish a tight holding relation between the warp head and the barrel.

With these and other objects in view which will appear as the description proceeds, the invention resides in the combination and arrangement of parts hereinafter described and set forth.

In the accompanying drawings, wherein two forms of the invention are set forth,

Fig. 1 is an elevation of a warp beam having the preferred form of the invention applied thereto.

Fig. 2 is a vertical transverse section on line 2—2, Fig. 1.

Fig. 3 is a vertical longitudinal section on line 3—3, Fig. 2.

Fig. 4 is an enlarged detailed horizontal section on line 4—4, Fig. 3.

2

Fig. 5 is a perspective view showing the form of wedge used in the preferred form of the invention.

Fig. 6 is a view similar to a portion of Fig. 2 but showing the modified form of the invention.

Fig. 7 is an enlarged detailed horizontal section on line 7—7, Fig. 6, and

Fig. 8 is a perspective view showing the wedge which is used in the modified form of the invention.

Referring particularly to Fig. 1, the warp beam designated generally at B, includes a barrel member 10, preferably a metal tube, having 15 external screw threads 11 cut on each end thereof. Each end of the barrel is provided with a warp head designated generally at H, and the left end of the barrel may have attached thereto a friction head 12 to cooperate with the let-off mechanism of the loom. Gudgeons 13 concentric with the barrel extend from opposite ends of the latter and afford means for mounting the beam in the warp winding machine and also in the loom. The warp heads are both 20 alike for each form of the invention, and the description will be limited to a single head for each form, namely, the head located at the left end of the barrel.

Referring particularly to Figs. 1 to 5 the head 30 H includes a flange member 15 having a flat warp thread engaging surface 16 which is perpendicular to the axis of the barrel member 10. The flange is provided with a hub 17 and a plurality of radial ribs 18. The hub is internally 35 screw threaded as at 19 to fit the screw threads 11.

As shown more particularly in Fig. 2, the flange 15 is provided with a pocket 20 defined by right and left side walls 21 and 22 connected by a third wall or bridge 23. The latter has an inner flat supporting surface 24 facing barrel member 10 and lying in a plane substantially parallel to the axis of the barrel 10 but spaced outwardly from member 10. This surface 24 45 preferably extends on both sides of a vertical plane passing through the barrel axis as viewed in Fig. 2, although this relation is not an essential for all forms of the invention.

A wedge member 25 having a flat smooth outer surface 26 in engagement with the aforesaid

surface 24 is mounted in the pocket 20 and has an internally screw threaded bore 27 in the low or narrow end thereof to receive a screw 28 freely rotatable in wall 21. Screw 28 has a head 29 which as shown in Fig. 2 engages the outer side of wall 21. A pin or disengaging means 30 extending through the screw 28 engages the inner surface 31 of the wall 21. The relation between the screw 28 and the wedge member 25 is such that when the screw is turned in one direction it draws the wedge toward wall 21 to establish tight holding relation with member 10. When the screw is turned in the opposite direction the wedge will be moved away from wall 21 due to engagement of the latter by pin 30.

As shown in Fig. 5 the upper surface 35 of the wedge is concave and provided with a plurality of grooves 36 to match or are configured to fit the screw threads 11 of the barrel 10. These grooves and the ridges 37 between them may constitute true screw threads having the same pitch and diameter as the screw threads 11, or they may be formed in any other manner, as by a milling operation, so that they will have a close fit with the screw threads 11 without necessarily being true screw threads.

As shown in Fig. 2 the wedge 25 is located to the left of the center of the beam with the high or wide part 38 thereof adjacent to the left end of the pocket 20 for engaging the screw threads 11. As a result of this relationship tightening of the screw 28 will draw the wedge 25 to the right, or laterally of the barrel member and in the direction in which screw threads 11 extend, see Fig. 2, thus forcing the left wide part of the wedge tightly against the screw threads 11. This tightening operation is effected after the head H has been turned on the screw 11 to the proper position along the length of the barrel, depending upon the width of the space between the heads H for the warp. When it is desired to change the position of the head the screw 28 will be given a reverse turn to effect loosening of the wedge 25, as already described.

The wedge has a flat lateral surface 40 engaging a flat surface 41 on web 42 of the flange 15, as shown more particularly in Fig. 4. When the wedge 25 is set in tight position the surfaces 40 and 41 engage each other so that any force acting on the lower part of the head H tending to deflect it will be resisted by the wedge. Reinforcing ribs 43 integral with the flange 15 connect with the side walls 21 and 22 and the bridge 23.

In the modified form of the invention a warp head H', similar to head H in many respects, has a wedge very similar to that of the preferred form except that instead of being drawn into tight holding engagement with the screw threads of the barrel it is pushed or forced into such engagement. Other parts of the modified form of the invention, except the wedge, and the screws for manipulating it, may be as already described for the preferred form of the invention.

The modified wedge, shown at 45 in Fig. 8, is formed with its small end solid and without the screw threaded bore 27. In other respects wedge 45 may be similar to wedge 25. The pocket 46, similar to pocket 20, is defined between right and left side walls 47 and 48 and a bridge or third wall 49 having a flat surface 50 similar to surface 24. Wall 48 has threaded thereto a pressure screw 51 having a head 52 and a lock nut 53. When it is desired to establish firm holding relation between the flange 54 of head H' and the barrel member the screw 51 is turned to push the wide

part of the wedge away from wall 48, or to the right as viewed in Fig. 6. After the desired setting of the wedge has been attained the lock nut 53 is tightened.

When it is desired to loosen the wedge 45 to move the flange 54 to a new adjusted position along the length of the barrel, the screw 51 is backed off and a loosening screw 55 threaded through the right wall 47, Fig. 6, is turned in a direction to effect left hand movement of the wedge 45, or movement in a direction which will move it away from holding relation with respect to the screw thread 11.

From the foregoing it will be seen that the invention sets forth a simple means by which the warp head of a warp beam may be very firmly connected to the barrel 10 in any adjusted position along the length of the latter. The means includes a wedge having screw threads or the like on one surface thereof configured to engage and fit the screw threads 11, and means are provided for moving the wedge into tight holding relation with the screw threads of the barrel. In the preferred form of the invention the wedge is drawn toward its holding position by screw 28, while in the modified form of the invention the wedge is pushed or forced into holding position by screw 51. In both forms of the invention the concave surface of the wedge which faces the barrel has a configuration which will fit the screw threads 11, and the wedge moves relatively to the warp head in the general direction in which the screw threads 11 extend.

Having thus described the invention it will be seen that changes and modifications of the foregoing specific disclosure may be made without departing from the spirit and scope of the invention.

What is claimed as new is:

1. In a warp beam having a cylindrical barrel member provided with external screw threads, a warp head having internal screw threads fitting the screw threads of said barrel member, means on the warp head having a flat surface substantially parallel to the axis of said barrel member but spaced from said barrel member, a wedge member slideable on said surface and having a concave surface configured to fit said screw threads of the barrel member, and means on the warp head to effect movement of the wedge member along said surface relatively to said head in a direction laterally of the barrel member to force the concave surface of the wedge member into tight holding relation with the screw threads of the barrel member.

2. In a warp beam having a cylindrical barrel member provided with external screw threads, a warp head having internal screw threads fitting the screw threads of said barrel member, walls on said warp head defining a pocket, a wedge located in said pocket and slideable on one of said walls in a direction laterally of the barrel member and in the direction in which the screw threads on said barrel member extend, said wedge having a concave surface adjacent to the barrel member configured to fit the screw threads of said barrel member, and means supported in another of said walls effective to move said wedge in said direction along said one wall and force the concave surface of said wedge into close holding engagement of the screw threads of said barrel member.

3. In a warp beam having a cylindrical barrel member provided with external screw threads, a warp head having internal screw threads fitting the screw threads of said barrel member, a wall on the warp head having a flat surface substan-

tially parallel to the axis of the barrel member but spaced from the latter, a wedge slideable on said surface in the direction in which the screw threads of said barrel member extend, said wedge having a concave surface configured to engage and fit the screw threads of said barrel member, another wall formed on said warp head, and screw means operatively related to said wedge and rotatable in said other wall to effect movement of said wedge in said direction to establish tight holding relation between said concave surface of the wedge and the screw threads of said barrel member.

4. In a warp beam having a cylindrical barrel member provided with external screw threads, a warp head having internal screw threads fitting the screw threads of said barrel member, a wall formed on said warp head and having a flat surface substantially parallel to the axis of the barrel member but spaced outwardly from said barrel member with respect to said axis, a wedge having a flat surface to engage said wall, said wedge having narrow and wide parts connected by a concave surface adjacent to and configured to fit the screw threads of said barrel member, and a screw mounted on said warp head and tapped into the small end of said wedge effective when turned in a given direction to move said wedge along said flat surface and move said concave surface into tight holding relation with respect to said barrel member.

5. In a warp beam having a cylindrical barrel member provided with external screw threads, a warp head having internal screw threads fitting the screw threads of said barrel member, a wall formed on said warp head having a flat supporting surface facing said barrel member and substantially parallel to the axis of the barrel member but spaced outwardly from said barrel member with respect to said axis, a wedge having a flat surface to engage and slide along said supporting surface, said wedge having narrow and wide parts connected by a concave surface adjacent to and configured to fit the screw threads of said barrel member, a second wall on said warp member, a screw mounted for free rotation on said second wall and having a head engaging a

side of said second wall remote from said wedge and outside said pocket, disengaging means rotating with the screw located in said pocket and engaging the opposite side of said second wall, rotation of said screw in a given direction drawing said concave surface of the wedge into tight holding relation with respect to the barrel member, said screw when rotating in a direction opposite said given direction acting because of said means by the engagement thereof with said opposite side of the second wall to cause movement of the wedge in a direction to disengage the latter from said barrel member.

6. In a warp beam having a cylindrical barrel member provided with external screw threads, a warp head having internal screw threads fitting the screw threads of said barrel member, three walls formed integrally with the warp head and defining a pocket, two of said walls being on opposite sides of the pocket and the third wall connecting said two walls and having a flat surface substantially parallel to the axis of the barrel member and spaced from said barrel member, a wedge located in said pocket engaging said flat surface and located between said two side walls, said wedge having a concave surface adjacent to the barrel member configured to fit the screw threads on said barrel member, a screw tapped into one of said side walls effective when turned in a given direction to move said wedge along said flat surface and force said concave surface of the wedge into close holding engagement with the screw threads of said barrel member, and a second screw tapped into the other side wall effective when turned in a given direction to move said wedge out of holding relation with respect to said barrel member.
